UNITED STATES PATENT OFFICE

MICHAEL E. BRADY, OF CHICAGO, ILLINOIS.

COLLAPSIBLE SHADE.

1,072,815.

Specification of Letters Patent.

Patented Sept. 9, 1913.

Application filed October 10, 1912. Serial No. 725,016.

To all whom it may concern:

Be it known that I, MICHAEL E. BRADY, a citizen of the United States, residing at Chicago, in the county of Cook and State of Illinois, have invented certain new and useful Improvements in Collapsible Shades, of which the following is a specification.

This invention relates to improvements in collapsible shades and is intended principally for use as a night shade.

The object of the invention is to provide a collapsible and easily portable shade which may be affixed to an ordinary gas jet or fixture for use in a sick-room where it is important to have a light immediately available and yet where it is desirable to prevent direct rays of light from reaching the patient, except at intervals.

In my invention I have provided a device which may be readily carried by a nurse in her hand bag and applied to the gas jet in a sick-room in such a manner as to cause the light from the jet to be reflected against the ceiling, thus providing indirect illumination in the room, and at the same time permitting, by a slight movement, the shade to be opened when full lighting effect of the gas jet is desired.

Other objects will be set forth and made apparent in the following specification and the accompanying drawing, in which—

Figure 1 is a side elevation of my device attached to a gas jet, the side being thrown open. Fig. 2 is a plan view of the same in closed position. Fig. 3 is an end elevation showing the device in collapsible position.

Like numerals refer to like elements throughout the drawing.

My device comprises preferably the three plates 10, 11 and 12, preferably trapezoidal in form, the side plates 11 and 12 each being hinged along a non-parallel edge at 13 and 14, respectively, to the main plate 10. The opposite non-parallel edge of the side plate 11 is provided with the groove 15. The outer edge of the side plate 12 is provided with the outwardly extending bead 16 adapted to seat in and be carried by the groove 15 when in what I term closed position, as indicated in Fig. 2. The upper edges of all three sides 10, 11 and 12 are overturned, as shown in Fig. 1 of the drawings, also the lower edges of sides 11 and 12.

The base 17, approximately triangular in form, is hinged at the base of side 10. This base is provided with a centrally located

aperture and a collar 18 extending upwardly from and around said aperture. Hinged to the inner face of side 10 above the base plate 17 is the triangular flap 20 having the centrally located aperture 21 and the downwardly extending collar 22 located there-around.

When attaching the device to a gas jet or lighting fixture 23 the latter is inserted through the aperture in the base plate 17 and the flap 20, the collars 18 and 22 serving to hold the device firmly in position on said gas jet.

It will be apparent that as shown in Fig. 1 the plates 17 and 20 will lie approximately in parallel planes and will serve to firmly retain the main plate 10 in fixed position. The side plates 11 and 12 are provided with the circular depressions 24 and 25, respectively, for a purpose to be described.

When the device is to be collapsed for carrying or shipping, the plate 20 is swung up into contact with the inner face of the main plate 10 and the base plate 17 is swung up into contact with the outer side of the main plate 10 as illustrated in Fig. 3. The side plates 11 and 12 may be swung flat against the respective surfaces of the main plate 10, the depressions 24 and 25 forming a seat for the collars 18 and 22, respectively, so that the device may be carried folded flat in a position which will occupy very little room. The device when attached to the gas jet or lighting fixture 23, as illustrated in Fig. 1, may have the side plates 11 and 12 in open position, as shown, in which case the full light of the jet will be allowed to penetrate the room in which it is located. When the sides 11 and 12 are swung up into contacting

position the bead or rib 16 may be seated in the groove 15 serving to retain the device shown in the position in Fig. 2, in which position the rays of light from the jet will be reflected upwardly, serving to shade the room, only indirect illumination being permitted. When the nurse or attendant finds it desirable to administer medicine or treat the patient, the side plates 11 and 12 may be disengaged and permitted to drop into the position shown in Fig. 1, in which event the direct rays of light will be permitted to strike the patient. To further the reflecting effect, the main and side plates 10, 11 and 12, respectively, are constructed of some such material as aluminum, which provides a highly reflective surface and at the same

time is of light weight and durable construction. In the event that the patient requires close examination during the night as for throat trouble etc., the main plate may be

5 so arranged with respect to the jet that the direct rays will be reflected directly toward the patient.

It will be apparent that by constructing these main and side plates trapezoidal in 10 form and arranging them as shown, the device will approximate a frusto-pyramid in shape and reflection of the rays upwardly will thereby be enhanced as will be apparent.

15 While I have shown and described my device with more or less particularity, I do not wish to be unduly restricted to such showing and description beyond the scope of the appended claims.

20 I claim:

1. In a collapsible shade, the combination with a main plate, of a plurality of side plates hinged to the side edges of the main plate, means for securing together the free 25 edges of said side plates, and a base plate hinged at one edge to one of said plates and provided with an aperture to engage with a lighting fixture and thereby support said shade.

30 2. In a collapsible shade, the combination with a main plate, of a plurality of side plates hinged to the side edges of the main plate, means for securing together the free edges of said side plates, and two parallel 35 base plates each hinged at one edge to one of said plates, said base plates being provided with alining apertures and adapted to engage a lighting fixture and thereby support said shade in distended condition 40 around the light.

3. A polygonal collapsible shade comprising a trapezoidal main plate with a plurality of trapezoidal side plates hinged to the non-parallel edges of the main plate 45 and adapted to have the free edges of the side plates swung into engaging contact to form a hollow polygonal sided frustum of a pyramid, and a base plate hinged at one edge to the main plate and provided 50 with a substantially centrally located aperture for engagement with and to permit said base plate to be supported by the desired lighting fixture.

4. A three-sided collapsible shade comprising a trapezoidal main plate with two trapezoidal side plates, one hinged to each of the non-parallel edges of the main plate and adapted to be swung into position so 55 that their free edges are in engaging contact so that the whole forms a hollow three-sided frustum of a pyramid, and a triangular base piece hinged to the main plate,

and provided with a centrally located aperture by which it may be engaged with the desired lighting fixture, substantially as described. 65

5. A three-sided collapsible shade comprising a trapezoidal main plate with two trapezoidal side plates, one hinged to each of the non-parallel lateral edges of the main plate and adapted to be swung into position 70 so that their free edges are in engaging contact to form a hollow three-sided frustum of a pyramid, a triangular base plate hinged to the main plate and provided with a centrally located aperture by which it may be engaged with the desired lighting fixture, and a second triangular plate provided with a centrally located aperture arranged in alinement with the aperture of the base 75 plate so that both apertured plates may engage with the desired lighting fixtures, substantially as described.

6. In a device of the class described, a main plate, a base plate carried by said main plate, said base plate being apertured and provided with a collar located around said aperture, and a second base plate located above the first base plate and provided with an aperture, said apertures in the base and 90 second named plates being in alinement and adapted to fit on a lighting fixture.

7. In a device of the class described, a main plate, a base plate approximately triangular in form and hinged at one edge to 95 said main plate, a second plate triangular in form also hinged at one edge to said main plate above said base plate.

8. In a device of the class described, a main plate, a base plate hinged at one edge 100 to said main plate, a second plate located above said base plate and hinged to the main plate, said base and second named plates being apertured and each provided with a collar around said apertures, and a 105 pair of side plates each hinged at one edge to the main plate and being provided with a depression adapted to fold over a collar on each side of the main plate, said base plate being adapted to be folded over on 110 to one side of the main plate under one of said side plates and said second named plate being also adapted to be swung over on the opposite side of said main plate, the collars on said base and second named 115 plates being adapted to seat in the depressions in said side plates.

In testimony whereof, I have subscribed my name.

MICHAEL E. BRADY.
